UNITED STATES PATENT OFFICE.

ROBERT M. ZEARING, JR., AND CHARLES J. OTTENTHAL, OF PHILADELPHIA, PENNSYLVANIA, ASSIGNORS TO SAID ZEARING.

FOUNTAIN SHAVING BRUSH.

Application filed December 24, 1921. Serial No. 524,767.

To all whom it may concern:

Be it known that we, ROBERT M. ZEARING, Jr., and CHARLES J. OTTENTHAL, citizens of the United States, residing in Philadelphia, Pennsylvania, have invented a Fountain Shaving Brush, of which the following is a specification.

Our invention relates to shaving brushes, and more particularly to improvements in that type of brush known as the fountain, and which comprises a reservoir or container for a shaving soap in the form of a cream or the like, and means for discharging the material from the container into the bristles of the brush.

One object of the invention is to provide a brush in which as many of the working parts as possible are permanently associated with the soap reservoir, thereby eliminating from the brush proper all complicating parts tending to prevent proper cleansing and maintenance of a sanitary condition.

Another object of the invention is to provide a novel form of container for the soap in the form of a cartridge adapted for insertion in the body of the brush, said cartridge possessing manufacturing advantages and comprising such elements as may be necessary for discharging the contained material.

A further object is the provision of a cartridge having means for discharging the contained material such that in its operation the cartridge is destroyed, thereby to prevent re-use as a container for the soap.

In the attached drawings:

Figure 1, is a transverse longitudinal section through the body of a brush and the cartridge contained thereby;

Fig. 2, is a transverse section on the line 2—2, Fig. 1;

Fig. 3, is a section on the line 3—3, Fig. 4;

Fig. 4, is a view in perspective of the cartridge, and

Fig. 5, is a view in perspective of details of the piston by means of which the material is fed from the cartridge.

With reference to the drawings, 1 indicates the tubular handle or body of the brush made in the present instance of sheet metal having pressed therein a thread 2 extending over the greater portion of the length of the handle, the latter having the bottom end 3 thereof enlarged, and said en-

larged portion having also a pressed thread 4 for the reception of an interiorly threaded cap 5 which is adapted to close the lower end of the handle. It will be noted that the cap 5 is substantially cup-shaped and has a threaded sleeve 6 whose threads correspond with the threads 4 of the lower portion 3 of the handle, the sleeve 6 being retained in the handle by the beaded over top edge 7 of the cover.

As clearly shown in Fig. 1, the handle portion 1 has at the top and secured thereto in such manner as to be capable of rotation with respect to the handle proper, a sleeve 8, there being a suitable recess in the interior of the said sleeve and at the bottom thereof for the reception of an annular extension 9 at the top of the handle 1, which annular extension is formed in the present instance by turning over the upper edge of the said handle. By means of this extension 9 and the formation of the sleeve 8, the latter, while being retained at the top of the handle, is capable of free rotational movement thereon. The upper portion of the sleeve 8 has, in the present instance 80 pressed therein, a thread 10 by means of which a cap 11 is secured at the top of the handle 1, said cap 11 being in the present instance, as in the case of the other parts of the device, formed of sheet metal and having a thread 12 pressed in the lower portion thereof corresponding to the threads 10 at the top of the sleeve 8. The cap 11 is also threaded at the top as designated by the numeral 13 for the reception of the internally threaded bristle-carrying member 14.

As best shown in Fig. 2, the cap 11 is apertured at the top, this aperture being in the form of a central circular opening 95 15 having extending from opposite sides rectangular slots 16, 16, and similarly the bristle-carrying member 14 is provided with a central opening 17 extending upwardly into the base of the bristles themselves. 100 The apertures 15—16 of the cap element and opening 17 of the bristle-carrying member are for the reception of the upper nozzle-like end 20 of a cartridge 18, which is adapted to be inserted in and to occupy the 105 interior of the handle 1. The said cartridge is best shown in Fig. 4, and consists primarily of a tubular casing 19 having at the

top the said nozzle-like extension 20, from the base of which at opposite sides extend wings or lugs 21, 21.

The body of the cartridge 19 is preferably made of waxed paper or the like, and has in the interior thereof a piston or plunger 22 which has extending from the sides blades 23 which pass through the sides of the cartridge and which have secured to the outer ends thereof and exteriorly of the cartridge a threaded sleeve 24, said sleeve in the present instance being of sheet metal and having the threads therein pressed to conform with the threads of the handle 1. The form of the piston 22 is best shown in Fig. 5, and the blades 23 are formed in the present instance by means of a single element 25, which is secured in the interior of the plunger and extend through slots 26, 26, in the opposite sides thereof. The corners of the element 25 are notched, as clearly shown in the drawings, and the sleeve 24 is so formed that its edges occupy the notches of the element 25, thereby being secured in place. The upper edges of that portion of the member 25 which passes through the sides of the cartridge are sharpened so that as the piston 22 is fed upwardly in the cartridge by means herein-after to be described, these edges cut the sides of the cartridge 19, as illustrated in Fig. 4. To assist in the rupturing of the cartridge, the latter may be scored on the line traveled by the blades.

As shown in Fig. 1, it is preferred to place a disk 27 of a comparatively soft material such as fibre or felt at the top of the piston 22, thereby preventing the passage of any of the contained material past the edges of the piston and its subsequent escape through the slits in the side of the cartridge. The cartridge 19 fits within the handle 1, as clearly illustrated in Fig. 1, the extension 20 passing upwardly through the openings 15 and 17 in the cap and bristle-carrying member respectively and having its upper end in which there is an aperture 28 established at the base of the bristles 29, the wings 21, 21, passing through the slots 16, 16, of the aperture 15, and thereby effectively preventing the turning of the cartridge 19 in the handle.

The operation of the device is as follows: A full cartridge is established as shown and described in the interior of the handle 1 and the cover 5 screwed into place whereby the cartridge is confined. When it is desired to discharge soap from the cartridge into the base of the bristles, the sleeve 8 or the brush-carrying element 14 is gripped with one hand and the handle 1 rotated with the other, the result being that the sleeve 24 the threads of which engage the threads of the handle 1 is fed upwardly in the handle together with the piston 22 in the in-

terior of the cartridge, this having the effect of expelling a portion of the contained material into the base of the bristles. When the piston 22 finally reaches the top of the cartridge 19, the cap 11 with its associated parts is unscrewed from the top of the sleeve 8, after which the expended cartridge 19 may be easily removed through the top of the casing, a new cartridge being inserted in the usual manner. 75

It will be noticed that none of the working parts of this device which come in contact with the soap, with the exception of the bristles themselves, is connected with the brush itself, these parts being associated with and forming a part proper of the cartridge 19. As a consequence, none of the parts of the brush is contaminated by the soap, and cleanliness is insured. This natural cleanliness is materially assisted by the construction of the brush, which provides for the separation from the handle of the brush-carrying member 14, and for the removal of the cap 11 and the cover 5, thereby leaving the body 1 in the form of an open-ended tube, the cleaning of which is an easy matter. The device has the further great advantage of providing a cartridge which is destroyed in use, thereby preventing its being refilled with a soap other than that originally contained. 90

We have described our invention in its preferred form, but it will be understood that considerable modification of the device is possible with no departure from the essential features of the invention. 100

We claim:

1. The combination with a casing having a discharge opening, of a container adapted to occupy the interior of the casing, and means for discharging a material from the container through the said discharge opening comprising a piston established in the container and having elements extending through the sides of the latter, a threaded member carried by said elements, and threads on the interior of the casing adapted to be engaged by the threads of said member whereby rotation of the casing with respect to the container advances the piston 115 therein.

2. The combination with an internally threaded casing, of an apertured end member detachably secured to the casing and rotatable with respect thereto, a container adapted for insertion in the casing and having means preventing relative rotation between itself and the said end member, a piston in the container, and elements extending through the sides of the container 125 and having threaded engagement with the interior of the casing.

3. The combination with an internally threaded casing, of an apertured member rotatably secured at the top thereof, a car- 130

tridge adapted to occupy the interior of the casing and having an apertured element extending into the aperture in said member, means for preventing rotation of the cartridge with respect to the member, a plunger in the cartridge, and an element secured to the plunger and extending through the side of the cartridge and having secured thereto a member threaded to correspond to the threads of the casing and in engagement therewith.

4. The combination with an internally threaded casing, of a threaded sleeve rotatably secured at the top of the casing, a threaded cap on the sleeve, said cap being apertured, a container for a plastic material adapted for insertion in the casing and having an apertured portion extending through the aperture in the cap, the cap aperture and the extending portion of the container being formed to prevent relative rotational movement between the cap and the container, means for retaining the container in the casing, a piston in the container having elements extending through the walls thereof, and an element secured to said latter elements and threaded to coincide with the internal threads of the casing.

5. The combination with a casing, of an element rotatably secured at one end thereof, an apertured cap detachably secured to said element, a cover for the opposite end of the casing, a container adapted for insertion in the casing, and means for feeding a

material from the container through the 35 aperture in the cap comprising a piston within the container having elements extending through the sides of the latter, and cooperating means upon said elements and upon the interior of the casing for advancing 40 the plunger in the container.

6. The combination with a member having an aperture, of a replaceable cartridge, a piston in the cartridge, an element fixed to the piston and projecting through the 45 side of the cartridge and adapted when the piston is advanced to slit the cartridge, and rotatable means exterior of the cartridge fixed against longitudinal movement and connected with the piston through the slit 50 in the cartridge formed by said projecting element for advancing the piston to expel the contents of the cartridge through said apertured member.

7. The combination with an apertured 55 member, of a replaceable cartridge, a piston in the cartridge, an internally threaded sleeve outside the cartridge rotatable with respect to the latter but fixed against longitudinal movement, and an element carried 60 by the piston and having threaded engagement with the sleeve and adapted when advanced by rotation of the sleeve to sever the cartridge and to advance the piston in the cartridge to expel the contents of the 65 latter through the apertured member.

ROBERT M. ZEARING, JR.
CHARLES J. OTTENTHAL.
